UNITED STATES PATENT OFFICE.

JOHN S. RATHBONE, OF MYSTIC, CONNECTICUT.

DESIGN FOR A SPOON.

SPECIFICATION forming part of Design No. 22,030, dated December 6, 1892.

Application filed October 22, 1892. Serial No. 449,703. Term of patent 7 years.

To all whom it may concern:

Be it known that I, JOHN S. RATHBONE, of Mystic, in the county of New London and State of Connecticut, have invented and produced a new and original Design for a Spoon, 5 of which the following is a specification.

Reference is to be had to the accompanying drawings, forming a part of this specification, in which similar letters of reference indicate

10 corresponding parts in both figures.

Figure 1 is a face view of a spoon, showing my design; and Fig. 2 is a back view of the same.

15 The essential feature of my design is the configuration and ornamentation of the handle of the spoon, such configuration and ornamentation consisting of a representation of

a bunch of the plant known as the "golden-rod," the stems A of which extend along the handle, and the flowers B form a wreath 20 around the enlarged upper end of the handle. The wreath incloses on the front of the handle a bust-like figure C of Washington, and the bowl of the spoon is ornamented by a shield D. A band E is wound around the 25 stems A of the plant.

I claim—

The design for a spoon, as herein shown and described.

JOHN S. RATHBONE.
